UNITED STATES PATENT OFFICE

100,541

DESIGN FOR A NAIL FILE

Frank P. Carpenter, Newark, N. J., assignor to Northam Warren Corporation, New York, N. Y., a corporation of New York

Application April 30, 1936, Serial No. 62,383

Term of patent 14 years

To all whom it may concern:

Be it known that I, Frank P. Carpenter, a citizen of the United States, residing at Newark, N. J., have invented a new, original, and ornamental Design for a Nail File of which the following is a specification, reference being had to the accompanying drawing, forming a part thereof.

In the drawing:

Fig. 1 is a front view of the nail file showing my new design, and

Fig. 2 is a rear view thereof.

I claim:

The ornamental design for a nail file substantially as shown.

F. P. CARPENTER.
